DESIGN FOR A COCKTAIL SERVER

Ben B. Manaster, Chicago, Ill.

Application November 25, 1940, Serial No. 96,786

Term of patent 3½ years

To all whom it may concern:

Be it known that I, Ben B. Manaster, a citizen of the United States and a resident of Chicago, in the county of Cook and State of Illinois, have invented a new, original, and ornamental Design or a Cocktail Server, of which the following is specification, reference being had to the accompanying drawing, forming a part thereof, and in which:

Fig. 1 is a perspective view of a cocktail server, showing my new design, which consists of a tray, and bottles, glasses, and an ice bucket positioned thereon in the manner shown; and

Fig. 2 is a top plan view of the same.

I claim:

The ornamental design for a cocktail server, as shown and described.

BEN B. MANASTER.
